UNITED STATES PATENT OFFICE.

ELROY STEIGERWALT, OF DUNKIRK, INDIANA, ASSIGNOR OF ONE-HALF TO JOHN G. WHITE, OF DUNKIRK, INDIANA.

HEATING DEVICE.

Application filed February 20, 1925. Serial No. 10,703.

The present invention relates to improvements in heater devices for automobiles.

A heater device of the above class consists of a metal receptacle or shell open at its front and closed at its rearward end and which is supported in position to surround a portion of the exhaust pipe from the engine, there being a conduit extending from the said receptacle, and through which conduit the warm air that has been generated in the receptacle, is conveyed to the interior of the car.

A problem in the use of such heaters, has been that of avoiding an overheating of the heater device itself, and of the consequent deterioration of same during the season when heat for the interior of the car is not required. Moreover there has been the hazard of injury and even combustion of parts of the car body due to heat transmitted from the body of the heater, during the time when same is not normally passing through the conduit and to the interior of the car.

The object of the present invention is to provide a heater device which is capable of being economically manufactured, and easily installed. A further object of the invention is to provide means combined with and which is a part of the receptacle structure, whereby the contents of the said receptacle may be permitted to freely escape, independently of the normal escapement thereof at such times as the heat contents are being delivered to the car interior.

The above general objects, and also certain more specific purposes of my invention are accomplished by the new construction, combination and arrangement of parts shown and described in the accompanying drawings and specifications. The invention is defined in the appended claims.

In the several views in the drawings, the different parts of the invention are identified by suitable characters of reference.

Figure 1 is a side view showing my improved heater device installed in operative position.

Figure 2 is a top plan view taken on the line 2-2 in Figure 1.

Figure 3 is a bottom plan view of the rear portion of the end-joint and neck of the receptacle, a portion of the closure sleeve being broken away.

Figure 4 is a detached enlarged detail view

showing the arrangement of the end joint, closure sleeve, and clamp device.

Figure 5 is an enlarged side view of the conduit head.

Figure 6 is a vertical sectional view on the line 6-6 in Figure 7, a portion of the control thimble being broken away.

Figure 7 is an enlarged top plan view of the conduit head.

Figure 8 is a plan view of the control thimble, the conduit being shown in section, and

Figure 9 is a sectional detail view of the connection for the control thimble.

The receptacle A in which the fresh air is received and contained, is made of sheet or cast metal, the former being preferred. Insulatory covering of asbestos may be used, if desired. For the exhaust pipe arrangement of cars of the ordinary or standard size, this receptacle may be about thirty inches in length and about three inches in diameter. The forward and rear connections of this receptacle are so devised, that in addition to their functions hereinafter described, they serve to support the receptacle on the exhaust pipe 2, in such alignment in relation to the floor 3 of the car, that right angle connections for the conduit that leads to the interior of the car, are available.

The forward end of this cylindrical receptacle is supported by a metal support bar B which is bent to the desired angle, as shown in Figure 1. This support bar is provided at its end with a U shaped yoke having the sides B'. Said yoke engages the top and sides of the inclined portion of the said exhaust pipe. The rear portion of the said receptacle is provided with a cone-shaped end joint A' which has an integrally formed neck A². The base of this end joint is so formed, and is connected at such angle, relative to the edge of the said receptacle, that neck A² is eccentric with the axial center of the receptacle. The said neck A² is adapted to fit the exhaust pipe, and may be of bifurcated form so that exhaust pipes of various diameters may be accommodated. In the bottom portion of the end joint is provided an opening A³. A metal closure sleeve C has an opening C³ and is provided with a neck C² which may be of divided formation and which fits the neck A² of the said end joint.

- A clamp collar D which is adapted to embrace the neck C², when drawn by bolt D¹ causes the neck A² to be firmly secured to the pipe, thereby holding the closure sleeve 5 at its set position on the end joint, and holding the receptacle at firm position with its neck A² on the exhaust pipe, and with the yoke B¹ at the inclined portion of the exhaust pipe.
- 10 A conduit, damper, and register arrangement, whereby the flow of heated air to the interior of the car may be controlled and at the same time may be independently released from the conduit, comprises a sheet metal conduit E which is adapted to fit in a neck rim A⁴ that surrounds an opening which is provided in the wall of the receptacle A. A circular head plate F of said conduit has flanges F' which are adapted to 15 rest on the edges of a hole provided for same in the floor 3 of the car. The said head plate F is of convex formation, as shown in Figure 5 and is provided with spaced openings F² as plainly shown in Figure 7. In the 20 walls of the conduit E are provided larger openings E² spaced apart as shown in Figure 5. The relative areas of these openings are determined in accordance with the variations in the area of the car interior.
- 25 A member to so cooperate that the openings F² are maintained closed while the openings E² are maintained open, is designated as a thimble, and it consists of a cylindrical metal shell G movable rotatively 30 in the said conduit. In the walls of this thimble are provided spaced apertures G², and in the top plate H (and which said top plate registers immediately underneath the head plate F of the conduit) are provided 35 apertures H² spaced to register with the openings E² of the conduit E, and with the openings F² of the head plate F respectively. The said top plate H of the thimble is 40 journaled on a pin J which is secured centrally of the head plate F, and is retained 45 at its set position by the pressure of a coil spring K. An upturned lug H³ is provided on the top plate H of the operator member or thimble so that the latter may easily be 50 shifted. The functions of the conduit E, and of the thimble, are apparent; the opening E² of the said conduit affording facility 55 for the escapement of the air contents of the receptacle A, and the openings F² of the head plate F affording facility for the passing of the air contents into the interior of 60 the car. I make no claim to the foregoing conduit and thimble construction, and while I consider it the preferred form of register or damper, it is understood that any suitable form of register and control device 65 may be used.

To install my invention, the muffler drum 4 is removed from the exhaust pipe. Receptacle A is then placed in position sur-

rounding the exhaust pipe, the yoke B¹ of the bar B, engaging the inclined portion of the exhaust pipe; the muffler drum is then replaced in its usual position, then by tightening the bolt D¹ the clamp D grips the 70 necks of the sleeve C and of the end joint A¹, thus holding the several parts securely together, and in cooperative engagement with the said exhaust pipe. The said receptacle is retained in such engagement 75 relative to said exhaust pipe, that free entry of the air at the forward end of same is assured and there is the utilization of the maximum area at the rear portion for the air which will have become heated by the 80 radiation from the exhaust pipe. The function of the opening A³ in the underside of the end joint, and which is kept normally closed by the closure sleeve C which is set at the position shown in the drawings, will 85 be presently referred to.

A circular hole of proper diameter having been cut in the floor of the car, the conduit E is lowered to its position of engagement with the rim A⁴, the flanges F¹ of the head plate F are then secured by suitable wood screws to the car floor. The normal position of the thimble is that shown in the drawings, the openings F² being closed, and the openings E² being open.

The effect of the heated exhaust pipe 2 is to cause the air that is drawn into the receptacle A to become warmed. Its free escape through the openings E² or through any other damper or register structure operates to prevent abnormal heating of the receptacle. When it is desired to have the warm air introduced to the interior of the car, the passenger by his foot or hand applied to the lug H³ simply shifts the thimble; by this shift of the thimble member, the openings E² will have become closed, and the openings F² will have become opened. The head portion of the conduit E, in combination with the shell portion of the thimble, then performs the function solely of a conduit, and the warm air is caused to pass upwardly and through the openings F². In varying the amount of warm air passing through the openings F², there is 100 coincidentally, a variation of the amount of escapement through openings E², so that any tendency of the receptacle to become overheated by reason of the shutting off completely or even partially, at the openings F², 105 is prevented.

It is obvious that the location, diameter, and length and formation of the conduit element, and the proportioning of the openings and apertures therein may be varied to suit requirements as may be suggested by the particular make of car upon which the invention may be applied. The conduit may extend from any desired location upon, or at any desired angle from the receptacle;

more than one conduit may be used if desired; and the head plate element of the conduit may be arranged to enter any desired part of the interior of the car.

5 During the season of the year when the heating of the car interior is unnecessary, the effect of the heat from the exhaust pipe in heater devices of this class as hitherto devised, is to raise the temperature of the 10 contained air to such abnormal degree, that the heater receptacle, besides becoming dangerously overheated, is rapidly deteriorated and impaired. The only way to prevent such impairment, and to avoid the 15 hazard of fire injury to the car, is to entirely remove the said heater device from the car. The foregoing disadvantages are overcome by my invention. Clamp D is loosened, the closure sleeve C is then set at 20 a position so that its aperture C³ registers with the opening A³ of the receptacle end joint. Thus, the air contents of the receptacle are permitted to escape freely and fully and any tendency of the receptacle to become 25 overheated, is avoided. My improved heater device while available at all seasons when heat for the interior of the car is desired, is out of the way, does not have to be removed, and requires no attention after 30 having been properly installed.

Wholesome air for the interior of the car is at all times assured, the used air being replaced by a continuous supply of pure outside air entering the front portion of the 35 receptacle.

My invention is easily capable of being handled economically in commercial handling and transportation to the trade, and on account of the low cost at which the 40 invention may be manufactured and installed for use, it is of utility for owners of cars of all classes.

What I claim as my invention and desire to secure by Letters Patent, is:

45 1. A heater device for automobiles, comprising a metal cylinder, a device to support the frontal portion of the cylinder in con-

nexion with an engine exhaust pipe, a cone shaped rear end joint having a divided neck to engage said pipe, there being an outlet 50 aperture in said end joint, a cone shaped sleeve to movably embrace said end joint and having an aperture to register with the outlet aperture of said end joint, and being provided with a divided neck to engage the 55 neck of the end joint, and a clamping device to bind said necks together and to said exhaust pipe.

2. A heater device of the kind described, comprising a cylindrical receptacle adapted 60 to be supported in position to surround an engine exhaust pipe, the front of said receptacle being open, a cone shaped rear end joint having its neck center at a point distant from the axial center of said receptacle, 65 there being an outlet aperture in said end joint, a sleeve movably mounted on said end joint to maintain the aperture in said end joint normally closed, there being an aperture in said sleeve to register with the aperture of the end joint, when the sleeve is shifted, and a device to secure the end joint and sleeve in connection with each other and to the exhaust pipe.

3. A heater device for automobiles, comprising a cylindrical receptacle, a flexible bar projecting from the front end of the receptacle and having a yoke to engage the top and sides of the engine exhaust pipe, said receptacle having a rimmed opening in 80 the wall thereof adapted to receive conduit connections, a rear end closure joint having an outlet aperture therein and being provided with a divided neck to engage the exhaust pipe, a sleeve movably retained on said closure joint and having an aperture therein 85 complementary to the aperture of the closure joint, the said sleeve being provided with a divided neck to engage the neck of the closure joint, a clamp to embrace the neck of 90 said sleeve, and means to draw the clamp to tightened position.
